(57) **CLAIM**

The ornamental design for a kibble, substantially as shown and described.

DESCRIPTION

FIG. 1 is a perspective view of the kibble, showing our new design;

FIG. 2 is a top plan view thereof;

FIG. 3 is a front elevational view of the kibble;

FIG. 4 is a side elevational view of the left side of the kibble, the right side being a mirror image thereof; and,

FIG. 5 is a rear elevational view thereof.

The bottom of the kibble forms no part of the claimed design.
